Davis & Dorsey

UNITED STATES PATENT OFFICE.

MARTIN THUM, OF ROCHESTER, NEW YORK.

ADJUSTABLE AND COMBINED FURNITURE.

1,195,627.

Specification of Letters Patent. Patented Aug. 22, 1916.

Application filed October 29, 1915. Serial No. 58,644.

To all whom it may concern:

Be it known that I, MARTIN THUM, a citizen of the United States, and resident of Rochester, in the county of Monroe and State of New York, have invented certain new and useful Improvements in Adjustable and Combined Furniture, of which the following is a specification.

This invention relates particularly to furniture of the kind in which a desk and a chair are combined as a unit, and in which provision is made for adjustment of the height of the desk.

In furniture for use in typewriting, or in the school-room, it has been proposed to mount a desk and a chair on separate legs or standards, but to connect them by a yoke or connecting-member of some form, so as to combine them into one unit, the connecting-member serving to retain them in the proper relation, and to cause them to afford mutual support, and the combined unit being movable as a single article of furniture.

One object of the present invention is to improve a combined article of furniture of the kind referred to in such a manner as to make it more comfortable and convenient for the user. In previous devices it has been proposed to mount the desk upon a central standard, and to connect that standard with the chair by a centrally-disposed yoke or rod, or to provide the desk with lateral supports or legs, and to connect the chair with one of these lateral supports. Both of these arrangements are unsatisfactory in point of the comfort and convenience of the user, however, since the first arrangement prevents the feet from being placed in the natural position on the floor directly in front of the user, while the second arrangement makes it difficult to enter and leave the chair except from one side, and this latter arrangement is inferior structurally in the matter of rigidity and strength.

In accordance with the present invention, I employ a central yoke, so as to produce a construction which is strong and rigid with the use of a minimum amount of material, but in place of providing the desk with a central standard to which this yoke is attached, I provide the desk with lateral supports or legs, leaving the space under the middle of the desk clear, and the yoke, which extends forwardly from the chair and close to, but clear of, the floor-surface,

curves upwardly under the desk to a point of attachment at the middle of the desk and at a substantial height above the floor-surface. Owing to this arrangement there is nothing to obstruct the space, beneath the forward part of the desk, in which the user's feet are naturally placed, while at the same time, owing to the low part of the yoke between the desk and the chair, the feet may be easily crossed, or moved from one side to another when a position of the body at an angle to the desk is desired, or in entering and leaving the chair from either side.

In the use of furniture of the kind in question for school purposes it is desirable that it be adjustable as to height, and another object of the present invention is to provide a simple, strong and convenient construction and arrangement of the parts for mounting the desk upon its legs or supports, and providing for a wide range of vertical adjustment in the desk. To this end I employ an arrangement in which the legs of the desk are connected by a transverse member at or near their upper ends, the legs and the transverse member thus constituting a rigid and unitary support, and in which the desk-body is arranged with a downwardly-open space, at the front, into which this supporting-member is received, the desk-body being vertically adjustable upon the support.

Where the desk of a combined desk and chair of the type in question is supported only by two lateral legs located near the front of the desk, I have found that when there is no one seated in the chair a downward pressure applied to the rear part of the desk may cause a considerable springing or distortion of the parts, and a corresponding tilting of the desk-top, owing particularly to the fact that when the chair is unoccupied there is no substantial obstruction to the sliding of the chair-legs over the floor-surface.

Another object of the present invention is to sustain the desk more rigidly against such movement, and to this end, in addition to the main supporting-legs of the desk, I provide supplementary legs, branching from the main legs and extending rearwardly therefrom, so as to afford points of support for the desk more nearly beneath its rear extremity. These legs are not, however, spaced so far from the main legs, at

their lower ends, as to prevent the desk and chair from having substantially the four-point support characteristic of the general arrangement of the invention.

5 Other objects of the invention, and the features of construction by which they are attained, will be set forth hereinafter in connection with the description of the illustrated embodiment of the invention.

10 In the accompanying drawings:—Figure 1 is a side-elevation, partly in vertical section, of a combined desk and chair embodying the present invention; Fig. 2 is a detail-view, in horizontal section and on a 15 larger scale than Fig. 1, showing particularly the connection between the desk and its supporting-member; and Fig. 3 is a perspective view of the combined desk and chair.

20 The invention is illustrated as embodied in a combined desk and chair in which the chair comprises a seat 5 and an adjustable back 6. The seat is mounted on a vertical stem 7, which is rotatable in a tubular 25 socket 8.

The desk comprises a front 9, sides 10, back 11, bottom 12, fixed top 13, and hinged cover 14, all formed and arranged in the manner common in school-desks, except that 30 the bottom 12 is cut away at its forward portion for a reason hereinafter described.

35 The combined desk and chair has four main points of support provided, respectively, by two laterally-extending legs 15, which immediately support the chair and are fixed at their upper ends to the socket 8, and two legs 16 which furnish immediate support to the desk and are located near the sides and front of the latter. The legs 40 prevent lateral tilting of the desk and chair, but for prevention of relative fore-and-aft tilting the desk and chair depend upon their mutual support, and for this purpose they are connected by a yoke 17 in the form of a 45 stout metal tube or rod. This yoke is rigidly fixed, at its rear end, to the socket 8 and the legs 15 of the chair, and it extends thence downwardly to a point near the floor. It is then curved upwardly to 50 ward the front of the desk, and is fixed to a transverse member in the form of a wooden board 18.

55 The board 18 constitutes a connecting-member between the desk-legs 16. Each of these legs is formed of sheet-metal bent in such a manner that the lower part is tubular, as shown in Fig. 1, while the upper part is channel-shaped, as shown in Figs. 1 and 2. The channel-shaped part of the 60 leg embraces the end of the board, and is provided, at its margins, with inwardly-directed flanges 19 which are buried in the wood of the board, while rivets 20 clamp the sides of the channel firmly against the 65 wood. By this construction the legs are at-

tached rigidly to the board 18, so that the legs and the board constitute a unitary rigid support for the desk.

The desk is mounted upon the support by means of brackets 21 formed of sheet-metal. 70 Each bracket is provided with a part 22 extending upwardly into the body of the desk, and the sheet-metal is bent, at its forward margin, to form an inwardly directed flange 23 extending vertically for a considerable 75 distance. In the angle between this flange and the body of the bracket the leg 16 is seated, and is vertically movable to provide for vertical adjustment of the desk-body.

The desk-body is adjustably fixed upon 80 the support by means of a through-bolt 24, which is seated in a slot in the rear surface of the board 18 and passes, at its ends, through vertical slots in the brackets 21, as shown particularly in Fig. 3, the bolt being 85 provided, at one end, with a nut 25 by which it may be tightened and loosened. The desk thus has a range of adjustment equal to the length of the slots in the brackets, and by extending the support upwardly into the 90 open space within the body of the desk, I am able to provide for a much greater range of adjustment than would otherwise be practical, while preserving a long bearing between the desk-body and the support such 95 as is necessary to insure a rigid connection between these parts.

The precise manner in which the yoke 17 is connected to the desk-support is not material to the present invention, but I have 100 shown a mode of connection substantially similar to that disclosed in my application for Letters Patent of the United States filed April 14, 1915, Serial No. 21,461. The forward end of the yoke is attached to the 105 board 18 by a horizontal pivot 26, and a stamped sheet-metal member or plate 27 is fixed to the yoke at a lower point, and provides arms extending laterally from the yoke. The ends of these arms are slotted 110 concentrically with the pivot 26, and are connected with the board by bolts 28. This arrangement is such that when the bolts are loosened the pivotal movement of the yoke, with respect to the desk, permits the four 115 legs 15 and 16 of the combined desk and chair to find firm bearings upon the floor-surface, regardless of any inequalities in the latter. This pivotal arrangement is not claimed in this application, however, as it 120 forms a part of the invention disclosed and claimed in my said application No. 21,461.

In order that the chair, when swung to one side or the other, may not come in contact with the desk and mar it, and also to 125 provide for vertical adjustment of the chair, the stem 7 is supported in the socket 8 by means of a collar 29, which is fixed to the stem by a pin 30. By providing a series of holes in the stem to receive the pin, various 130

positions of vertical adjustment in the chair are provided for. The collar has a downwardly projecting portion 31, forming two shoulders which coöperate with a fixed stop-lug 32, and thus a rotative movement in either direction is arrested before the chair-back can come into engagement with the desk.

In order to support the desk more firmly against downward pressure on its rear portion, particularly when the chair is not occupied, I employ supplementary legs 33, which branch rearwardly from the desk-legs 16, and engage the floor a short distance in the rear of the latter. These supplementary legs are braced by horizontal rods 34 connecting their lower portions with the legs 16. While these supplementary legs effectively serve the intended purpose, they do not substantially interfere with the comfort of the user of the desk, or the convenience of ingress or egress, nor are they spaced at a sufficient distance from the main desk-legs 16 to substantially interfere with the accommodation of the combined desk and chair to inequalities in the floor-surface, as above described.

My invention is not limited to the embodiment

thereof hereinbefore described and illustrated in the accompanying drawings, 30 but it may be embodied in various other forms within the nature of the invention as it is defined in the following claims.

I claim:—

1. The combination, with a desk-body, of 35 a bracket attached thereto at each side thereof and extending downwardly therefrom and upwardly therein, each bracket having at its forward margin an inwardly-directed flange, a support for the desk-body comprising legs and a connecting member, said legs being arranged between said brackets and their flanges, and means for adjustably securing said desk-body to its said support.

2. The combination, with a desk-body, of 45 a support therefor comprising legs and a connecting member, said legs being formed of sheet metal bent into channel shape at their upper parts to receive the ends of said connecting member and having marginal 50 flanges bent inwardly toward each other which enter the connecting member on each side thereof, and means for fixing said support to said desk-body.

MARTIN THUM.
